UNITED STATES PATENT OFFICE.

ERNEST K. HOOD, OF INDIANAPOLIS, INDIANA; HARRIET H. HOOD ADMINISTRATRIX
OF SAID ERNEST K. HOOD, DECEASED.

OPERATING MECHANISM FOR SLICING-MACHINES.

1,340,829.

Specification of Letters Patent.

Patented May 18, 1920.

Application filed January 4, 1919. Serial No. 269,636.

To all whom it may concern:

Be it known that I, ERNEST K. HOOD, a citizen of the United States, residing at Indianapolis, county of Marion, and State of Indiana, have invented certain new and useful Improvements in Operating Mechanism for Slicing Machines, of which the following is a specification.

The object of my invention is to provide a power driven slicing machine wherein there is no shock produced by picking up the reciprocating and rotating parts of the machine, and also to provide a machine which can be operated either by hand or power and accomplish these results.

My invention consists in the following arrangements of parts to accomplish these results:—

My invention can be applied to any type of slicing machine using a rotary knife.

In the drawings—

Figure 1 is a plan of an ordinary slicing machine equipped with my improvement.

Fig. 2 a plan of a motor unit equipped with my improvement, and

Fig. 3 a cross section of the same.

The numeral 1, represents the bed of a slicing machine; 2 the rotary knife; 3 the reciprocating carriage; 4 the feeding mechanism; and 5 the ordinary, hand operating wheel.

The operation of this type of machine is well known and needs very little explaining.

The meat, or other substance to be cut is clamped in carriage 3. The hand wheel 5, is rotated, which causes knife 2, to rotate and carriage 3, to reciprocate. The feeding mechanism 4, feeds the meat, to be cut, toward the plane of rotation of the knife, and by setting the feeding mechanism to the desired thickness the meat is cut uniformly and of the required thickness. These operations are universal with this type of slicing machine and I make no claim thereto.

It is very desirable in slicing machines to have a positive driven motor connection and a hand operating mechanism each of which can be operated without disconnecting the other, and I have also found that it is desirable to have the shock occasioned by throwing on the motor absorbed before the reciprocating and rotary parts of the machine

are picked up. To accomplish this I loosely mount a sprocket or gear 6 on the hand operating shaft. This sprocket is held from end play by a collar 7, and is connected to hand operating wheel 5, by means of a coil spring 8. Thus it will be seen that when power is transmitted to sprocket 6, through chain 9, the spring 8, absorbs any initial shock, before transmitting the power to hand wheel 5, and the rotating and reciprocating parts of the slicing machine are picked up without shock.

In practice the motor or driving unit operating chain 9 is provided with a forward running positive driving clutch.

In Figs. 2 and 3, I have shown my invention applied to the motor driving unit.

10 represents a motor, carrying a worm, 70 meshing with a worm wheel 11, mounted in a housing 12. This worm wheel is provided with abutments 13 adapted to contact with pawls 14, carried by a shaft 15 which is driven through these pawls when the worm 75 wheel is operated in the proper direction. However, shaft 15 can be operated in the same direction without operating worm wheel 11, because the pawls 14 operate as a forward running clutch.

Loosely mounted on shaft 15, is a sprocket 16, held from end play by a collar 17.

Rigidly mounted in the end of shaft 15, is a collar 18, connected with sprocket 16, by means of a coil spring 19.

It will thus be seen that any power from motor 11 is transmitted to sprocket 16, through spring 19, and that the shock of picking up the load, carried through the chain leading from the slicing machine to 90 the sprocket 16, is absorbed by the spring 19.

In practice it has been demonstrated that with this arrangement the load is picked up without noise or vibration.

The forward running clutch construction 95 above described forms the subject matter of application filed by myself and W. B. Wolff as joint inventors.

I claim:

1. The combination in a slicing machine 100 of a hand operating device; a power driving unit; a resilient connection between the slicing machine and the operating means; and means whereby the machine can be op-

erated by either or both driving means, substantially as and for the purpose set forth.

2. In a slicing machine the combination of a hand operating device; a driving member loosely mounted adjacent to said hand operating device; a spring connecting said loosely mounted member and the hand operating device; and a power driving unit

connected with the loosely mounted member, substantially as and for the purpose set forth.

ERNEST K. HOOD.
